UNITED STATES PATENT OFFICE.

EDWARD D. WOODS, OF CLEVELAND, OHIO, ASSIGNOR OF ONE-THIRD TO FREDERICK SCHUSSLER AND C. BERTHA SCHUSSLER, BOTH OF BRIDGEPORT, CONNECTICUT, AND ONE-THIRD TO WILLIAM HEYMAN, OF DETROIT, MICHIGAN.

MENDING DEVICE FOR CHAINS.

1,279,066.

Specification of Letters Patent. Patented Sept. 17, 1918.

Application filed June 15, 1916. Serial No. 103,723.

To all whom it may concern:

Be it known that I, EDWARD D. Woods, a citizen of the United States, and resident of Cleveland, in the county of Cuyahoga and 5 State of Ohio, have invented certain new and useful Improvements in Mending Devices for Chains of which I hereby declare the following to be a full, clear, and exact description, such as will enable others skilled in 10 the art to which it appertains to make and use the same.

The objects of the invention are to provide a combined mending device for a chain, which serves also at the option of the user 15 as an additional link, or as a terminal hook for the chain and can be used in emergencies for either purpose.

It is also a compact and serviceable device and its use will not lessen in any way the 20 strength of the chain but may rather serve to increase its tensile strength.

The invention comprises a pair of S-shaped links spaced apart upon a common central support, and having their extremities 25 so shaped that a chain link can be inserted between them only on one side of the device and can only be withdrawn from the other side and are so shaped as to prevent accidental separation of the links under all 30 varieties of use of the chain.

The invention further includes the combination and construction of the several parts hereinafter described, shown in the accompanying drawings and specifically 35 pointed out in the claims.

In the accompanying drawings Figure 1 is a plan view of the device showing the upper face; Fig. 2 is a side elevation thereof; Fig. 3 is a bottom view.

40 In these views A and A' are the two S-shaped members, each preferably formed of sheet metal wider at the center and tapering toward each end.

These S-shaped members are centrally 45 connected by means of the heavy rivet B.

In Fig. 1 a chain link c is shown in dotted line entering the tapered extremity a of one end of the upper of the S-shaped members. This extremity is slightly turned

50 upward at the end to permit the introduction of the link, which passes around the curved end of this member until it comes opposite an opening a' between the curved end a' of the other or lower member, and the

edge a³ of the body thereof or common shank 55 of the hooks. The chain link can then be dropped through this opening until its loop enters between the two S-shaped members, and the sides of the loop encircle both members. 60

It cannot therefore be withdrawn immediately from the extremity of the upper member owing to the fact that the extremities of the upper member are longer than the extremities of the lower member, and therefore the extremities are reversed in position 65 in the respective members and there is not space enough between the long extremity and the body of its respective member to permit releasing the loop from that member. 70 The open space a' however permits depressing the chain loop so as to first release it from the lower member A', when of course it can be moved along the curve of the other member A and finally withdrawn in the 75 same manner that it was inserted at the extremity a.

This action requires first bringing the loop to register with an opening a', then depressing it to clear it from the corresponding member A', then moving it about the curved end of the other member A' and withdrawing it at a from the tapering end thereof. 80

This succession of movements required to 85 remove a chain link from both the S-shaped members provides perfect protection from accidental separation of the parts.

The device can be carried in the pocket to replace a broken link temporarily and thus 90 prevent delay in the work or can be used continuously as a link in the chain, and since it is double and the pulling strain is received upon the edges of the members the new link 95 may be stronger than the other links of the chain.

When the device is employed as a terminal hook, the chain link is passed over the point a to the center of the curve and remains there and is held from coming out by means 100 of thickened sides a², a² of the part a, and a thickened portion a³ of the body of the other member.

This hook can easily be made as strong as the chain, and when made of properly 105 toughened sheet steel is light and portable, and can be carried in the pocket.

Applicant's S-shaped links are stationary

and spaced apart, and the eye or chain link can be inserted in one way, first over the long extremity, then around to the short extremity, then transversely over the short extremity, and back over both of them.

Having described the invention what I claim as new and desire to secure by Letters Patent is:

1. A link member comprising two parallel relatively immovable S-shaped members spaced from each other, a central rigid connection preventing the rotation of one member upon the other, one S-shaped member having shorter extremities than the other, said link member attachable to a second link or eye by first passing the loop of said eye over one of said longer extremities, next moving it around said longer extremity until it can be moved transversely of the short extremity and back over both of the extremities, said link being detachable therefrom by means of a reverse movement, substantially as described.

2. A mending device for a chain, comprising a pair of parallel S-shaped members, and a central connecting member, the extremities of one of the members being shorter than the extremities of the other member, providing openings between said shorter extremities and the body of its respective S-shaped member, through which a chain link can be withdrawn from said member, the longer extremities being outwardly bent to permit the introduction of said link.

3. A mending device for a chain, comprising a pair of relatively immovable parallel S-shaped members spaced apart, and a central member rigidly connecting said S-shaped members together, the hooked extremities of one member being shorter than the hooked extremities of the other member, whereby openings are provided between said shorter extremities, and the central shank of the same, through which a link can be withdrawn from said shorter member, and finally over one of the extremities

of the other S-shaped member and said link removable by means of the reverse operation.

4. A mending device for a chain, comprising a pair of relatively immovable parallel S-shaped members, and a central spacing member connecting said S-shaped members together, the hooked extremities of one member being shorter than the hooked extremities of the other member, whereby openings are provided between said shorter extremities, and the central shank of the same, through which a link can be withdrawn from said shorter member, and finally over one of the extremities of the other S-shaped member, the extremities of the longer member being shaped to permit the introduction of said link thereover.

5. In a chain mending device, a separate detachable and attachable link, comprising relatively immovable parallel spaced S-shaped members, one member having long extremities over which a link of said chain can be introduced, and the other having shorter extremities providing openings through which said link can be withdrawn and a central connecting means for said S-shaped members.

6. In a chain mending device, a separate detachable and attachable link, comprising parallel spaced S-shaped members, one member having long extremities over which a link of said chain can be introduced, and the other having shorter extremities providing openings through which said link can be withdrawn, and a central connecting means for said S-shaped members, said longer extremities and the body therefor being thickened adjacent to the point of insertion for said link.

I testify whereof, I hereunto set my hand this 3d day of May, 1916.

EDWARD D. WOODS.
